FINISHING TOOL

Filed Aug. 8, 1929

UNITED STATES PATENT OFFICE

WILLIAM C. JONES, OF OAKLAND, CALIFORNIA

FINISHING TOOL

Application filed August 8, 1929. Serial No. 384,407.

This invention relates to an improved tool or instrument which is especially designed for use by persons generally known in the trade as furniture finishers, and it has particular reference to the species of tool which is employed for heating and melting wax, to fill up crevices, blemishes, and other demolished looking spots on the surface of the furniture.

10 Briefly stated, the invention has particular reference to a simplified instrument comprising an especially constructed handle and an especially designed blade including electrical means for heating the point of the 15 blade as desired, in order to enable it to be manipulated in a satisfactory manner for melting the wax or other finishing material generally used for patch up work.

More specifically stated, I have evolved 20 and produced a simple and inexpensive tool which may be employed in a dependable manner and with great facility and efficiency for the purpose stated, wherein the same includes a handle having a double arrangement of switches; namely a main control or 25 cut out switch, and an automatic spring opened switch for intermittent use, together with an appropriately shaped blade to accomplish the work constructed to accommodate 30 an electrical heating element, at the point of the blade.

Other features and advantages will become more readily apparent from the following description and drawings.

35 In the drawings:

Figure 1 is an elevational view, partly broken away, showing a tool constructed in accordance with the invention.

Figure 2 is a central longitudinal section 40 through the same.

Figure 3 is a transverse section through the blade, the section being on the line 3—3 of Figure 1.

Figure 4 is a top plan view of one of the 45 sections of the blade.

The reference numeral 5 designates generally the handle, which may be of any appropriate material and configuration, the same preferably including a body portion 6 and a separable end portion 7. At the juncture of

the portions 6 and 7 there is an opening provided to accommodate the current supply cable 8, which receives its source of supply from any appropriate means (not shown). Inside of the section 7 and at one end is the 55 main control switch 9. This includes a sleeve lining 10 into which a cap 11 is threaded. The cap constitutes a mounting and guide for the push-pull pin 12, having an insulated portion 13 and handle, together with a head 60 14 of electricity conducting material. This constitutes the movable part of the switch and is cooperable with the spring contact fingers 15. Thus the current may be turned on or off as desired. The cable is arranged 65 within the handle to provide a heating element as at 16, this being confined between the pointed ends of the sections 17 and 18 of the curvate blade 19, and so arranged there- 70 between as to concentrate the heat at the point of the blade. This blade is of appropriate material and preferably comprises sections of the cross section shown better in Figure 3. The section 17 is of generally rectangular cross section and has bevelled longitudinal edges 20. The section 18 is of external convex configuration. These sections are fastened together by a suitable fastening in the nature of a screw 21. The reference 75 character 22 designates an insulating bushing within the handle which accommodates the shank portion of the blade, while the reference character 23 designates the operator's control switch. This comprises an appropriate casing 24 for the contact (not shown) 80 and a spring push button 25. The button is normally in a position to hold the switch open, and the operator merely presses the button in when it is desired to keep the heating element 16 in operation. This allows the 85 degree of heat at this point of the blade to be controlled at will. This double switch arrangement makes the tool quite advanta- 90 geous.

From the foregoing it will be seen that the 95 invention resides in the provision of an electrically heated knife, capable for use by various tradesmen, such as form builders, and others, where a knife of this character would be found useful, and that a further advantage 100

of a knife of this nature, is in the provision 5 of the blade so constructed, that the filament 16 is located in the actual tip of the point of the knife to directly heat the point of the knife, rather than some other portion of the knife which results in the actual tip being heated only by conduction or radiation which is the customary practice. Directly heating the point of the blade obviates the danger of 10 the handle of the knife becoming heated, since the heat as before pointed out is confined in the tip of the blade.

Furthermore, the blade of this knife, as 15 described and illustrated, is so constructed that one may perform very delicate work of the finest quality, even when in the hands of the unskilled.

The particular arrangement of the blade, 20 that is the flattened curvate construction as well as the longitudinal curvature is such as to enable the work to be carried on expeditiously and in an efficient and dependable manner. The advantages, use and other features will be quite clear to persons skilled 25 in the art after considering the invention in connection with the drawings. Therefore, a more lengthy description is believed to be unnecessary.

Minor changes in shape, size and re-arrangement of parts coming within the field of 30 invention claimed may be resorted to, in actual practice, if desired.

I claim:

1. In a structure of the class described, a 35 handle of uniform cylindrical form, an insulating bushing in said handle, a curvate sectional blade having a shank portion mounted in said bushing, said blade being composed of a flat faced longitudinally curved inner section, and a convex longitudinally curved outer section; and a grip operated switch of the 40 spring and button type adapted to be intermittently operated and mounted in the lower wall of the handle, near one end, and a push 45 and pull type of current cut out switch mechanism, forming a closure in the other end of the handle, together with electrical conduit in said handle and embedded in said blade, a relatively small electrical heating element 50 embedded in the neck of said blade for heating and maintaining the tip portion of the blade at the desired temperature immediately controlled by said intermittent grip operated push button switch.

55 2. In a finishing tool of the class described, a handle, a curved blade, plano-convex in cross section and having a rounded tapering tip and electrical heating means confined to the extreme point portion of said blade.

60 3. In a finishing tool of the class described, a handle, electrical conduits in said handle, a blade, electrical conduits inserted in the blade, and in circuit with the conduits with the handle, said blade being curved and 65 provided with a pointed extremity, and elec-

trical heating means located within the extreme tip portion of the blade, and a push and pull type switch carried by said handle controlling the flow of electrical current to said conductors in said handle, and an intermittently operated switch in the lower part of said handle to intermittently control the flow of electricity through said heating element to maintain the desired temperature at the will of the operator.

In testimony whereof I affix my signature.

WILLIAM C. JONES.
